UNITED STATES PATENT OFFICE.

CHRISTIAN VIEMAN, OF MICHIGAN CITY, INDIANA, ASSIGNOR OF ONE-HALF
TO HENRY W. JOHNSON, OF SAME PLACE.

ROTARY ROCKING-CHAIR.

SPECIFICATION forming part of Letters Patent No. 246,431, dated August 30, 1881.

Application filed January 26, 1880.

To all whom it may concern:

Be it known that I, CHRISTIAN VIEMAN, of Michigan City, county of La Porte, and State of Indiana, have invented a new and useful Improvement in Rotary Rocking-Chairs, which is fully set forth and described in the following specification, reference being had to the accompanying drawings, in which—

Figure 1 represents a side elevation of a chair embodying my improvements; Fig. 2, a rear view of the same; Fig. 3, a vertical section of the same on the line xx , Fig. 1; and Fig. 4, a transverse section of the same, taken on the line yy , Fig. 1, giving a plan view of the base of the chair.

My invention relates to that class of chairs which both rock and turn on a swivel; and it consists in an improved mode of attaching the chair to its base; also, in a fastening device to prevent the rocking of the chair when desired; and, also, in an improved mode of attaching both chair and base to the standard or support, all of which will be hereinafter more fully explained, and pointed out definitely in the claims.

In the drawings, A represents the chair proper, on the bottom of which, on each side, are attached the rockers a. These rockers are united at their middle by a cross-bar, a'.

B is the base of the chair, having upon its sides rocker-ways b, formed of strips of rubber band tacked or otherwise firmly attached to the base B. Underneath the base, at its center, is rigidly attached the hollow pin b², which fits into the socket of the standard, in which it revolves when required.

C is the standard or support, and is of the ordinary construction.

Tenons a² are formed on the under side of the cross-bar a', just inside the rockers, and which fit loosely into mortises b' underneath, in the base B, thus holding the chair in place and limiting the distance both backward and forward which the chair is permitted to rock.

D is a swivel-rod, which passes upward through holes in the centers of the standard C, pin b², base B, and cross-bar a'. Wound around its lower end is the coiled spring d, which is held in place by the head d' on the

end of the rod and shoulders c within the standard C.

E is a metallic sheath, fastened underneath the standard C. The interior diameter of this sheath is larger than that of the hole at the bottom, which is only sufficiently large to permit of the ready entry of the swivel-rod D with its head d'. The interior recess thus formed is lined with stiff paper or other suitable packing, e, to prevent the grating noise caused by the friction of the head d' against another metallic surface.

F is a short metallic bar, round at its ends and enlarged at its center, at which point the upper end of the swivel-rod D passes up through a hole. This bar is raised a short distance above the cross-bar a', and its ends rest in supports or bearings a³, attached to the top of the cross-bar a'. A nut, d³, and washer d³ are placed on the upper end of the swivel D, holding it in place and furnishing a ready means for the adjustment of its length and the tension of the coiled spring d.

To the rear of the base B is attached the short horizontal rod b³, having its end flattened, so as to engage in rectangular holes g in the short metallic strap G, hinged to a staple underneath the back of the chair-seat A. When the rod b³ is thus engaged in the strap G the chair-seat A is locked so that it cannot be rocked. When it is desired to rock the chair the strap G is raised off the end of the rod b³ to a horizontal position and swung around under the chair-seat into the catch g'.

The construction above described is at once simple, cheap, and durable, combining in one the advantages of both a swivel and a rocking chair.

Having thus described my invention, what I claim as new, and desire to secure by Letters Patent, is—

1. In a rotary rocking-chair, the seat A, provided with rockers a, in combination with the swiveling base B, provided with ways for the rockers, the standard C, having a central tube, and the single swivel-rod D, substantially as 90 and for the purpose set forth.

2. The combination of the seat A, provided with rockers a, cross-bar a', provided with ten-

ons a^2 , base B, having mortises b' , swivel-rod D, bar F, supports a^3 , spring d, and standard C, substantially as described.

3. The combination of the seat A, provided with rockers a , cross-bar a' , and tenons a^2 , base B, provided with mortises b' and rubber rock-er-ways, b, the tubular pin b^2 attached to the base, swivel-rod D, provided with a head, d' ,

at its lower end, bar F, mounted loosely on supports a^3 , standard C, and spring d, all ar-ranged and operating substantially as de-scribed.

CHRISTIAN VIEMAN.
